UNITED STATES PATENT OFFICE.

PAUL F. COX, OF CHICAGO, ILLINOIS.

WEB-PRINTING PRESS.

Application filed May 9, 1921. Serial No. 467,959.

To all whom it may concern:

Be it known that I, PAUL F. Cox, citizen of the United States, residing at Chicago, in the county of Cook and State of Illinois, have invented certain new and useful Improvements in Web-Printing Presses; and I hereby declare that the following is a full, clear, and exact description thereof, reference being had to the accompanying drawings, which form part of this specification.

This invention relates to printing presses of the so-called traveling cylinder flat bed web perfecting type in which the cylinders are moved back and forth over stationary type beds and impress the web upon flat forms of type or printing surfaces on said beds.

The principal object of the invention is to provide a press which will be very compact, will be very simple in construction, efficient in operation, and can be operated at high speed as compared with presses heretofore designed for doing the same class of work.

In this new press the two beds are arranged in the same horizontal plane and in close proximity to each other with one of the beds lying between the main crank gears or wheels by which the cross heads in which the cylinders are journaled are reciprocated, to move the cylinders back and forth over the beds. This arrangement results in shortening the length of the press several feet, and such shortening of the press also enables various other simplification of construction and lessening of parts as hereinafter pointed out.

Both type beds are arranged upon the same level at a convenient height from the floor so that they are readily accessible when the pressman desires to place type forms upon or remove them from the beds; and this eliminates the necessity for any "pit" customarily provided for other types of traveling cylinder web printing presses. It also enables the pressman to change the color in both ink fountains while the press is in operation which is an advantage and time saving feature which will be readily appreciated by the trade.

By having one of the type beds set between the main crank wheels one of the cyl-

inders travels back and forth between the main crank wheels, and thus the space ordinarily required merely for the main driving system is utilized for printing, and this construction permits the arrangement of all the infeeding and outfeeding cylinders and co-acting devices in convenient and compact space, easily accessible for all purposes from the drive end of the press.

This invention also enables a large web roll to be placed at the end of the press at the end opposite to the drive end, thus leaving a clear floor space for the operator when overcasting or threading the web in the feed and delivery mechanism and around the angle bars to the folder. In the present invention the folder is located at the side of the press adjacent the drive end thereof and the folding mechanism is driven directly from the main crank gears of the machine and in exact time therewith.

In the form of press shown the cylinders are single acting, or print only on one strike instead of on both strokes over the beds and the invention includes novel means for raising and lowering the impression cylinders on their alternate strokes; and also novel means for tensioning the web uniformly from the web roll throughout the press to the delivery. Other novel features and improvements will be hereinafter described.

In the accompanying drawings I have illustrated one practical embodiment of the invention and will describe the same in detail with reference thereto and set forth in the claims the essentials of the invention, and the novel features of construction and novel combinations of parts for all of which protection is desired.

In said drawings;

Fig. 1 is a side elevation of the complete press.

Fig. 2 is a longitudinal vertical section thereof.

Fig. 3 is a drive end elevation of the press.

Fig. 4 is a detail view of the driving connections between the folder cylinders and the crank gear.

The press shown in the drawings is adapted to produce and fold newspapers of 4, 6

and 8 pages of standard news paper size. The press has opposite side frames L between which are mounted two beds O and O² which are arranged in the same horizontal plane end to end. Cooperating with these beds are impression cylinders I and I². The impression cylinder I is journaled in cross heads G which are slidably supported in guides K on the side frames L. The impression cylinder I² is journaled in cross heads G² which are slidably mounted in guides K² in the side frames L.

The cross heads G and G² at each side of the machine are rigidly connected by a tie bar M so that they move as one. The cross heads are reciprocated longitudinally of the press, (so as to roll the cylinders back and forth over the beds) by means of pitmans E each connected at F to the cross head G and at D² to a wrist pin on a main drive gear C which is rigidly keyed to a main drive shaft C² suitably journaled in bearings in the side frames. The drive gears C mesh with pinions b on a main drive shaft A which may be driven by any suitable means. As shown it carries a pulley A¹ driven by a belt A³ from a motor A², which may be conveniently located beneath the bed N.

The cylinder I is journaled in boxes H mounted in eccentrics J which are provided with two arms P and R; the arm P carries a roller which is adapted to engage a fixed cam Q attached to the main frame just as or before the cross heads G reach the inward limit of their movement. Similarly the shaft H² of the cylinder I² is journaled in eccentrics I³ which are provided with arms P² and R². The arm P² carries a roller which is adapted to engage a fixed cam Q² attached to the frame of the press, just as or before the cross heads G² reaches the inward limit of its travel. The arms R and R² are connected by a tie rod R⁴ so that when one eccentric is rocked the other eccentric is similarly rocked. Thus the cylinders are thrown on and off impression by alternate engagement of the arms P and P² with the cams Q and Q² respectively on the alternate strokes of the cross heads or cylinders.

The bed O² is practically arranged above the main drive shaft C² and between the main crank gears C so that the cross heads G² which move the cylinder I² move between the gears C this arrangement materially shortens the length of the press, by bringing driving mechanism practically underneath or beside one of the beds.

The cross heads G carry a system of inking rollers hereinafter referred to at the outer side of cylinder I, and the cross heads G² carry a system of inking rollers hereinafter referred to at the outer side of cylinder I².

65 The cross heads G carry a shaft i on

which is mounted arms h' carrying a web guide roller b⁸. Cross heads G also carry arms h² in which is supported a web guide roller b¹⁰.

The rollers b⁸ and b¹⁰ are arranged above 70 and at opposite sides of the cylinder I. A web guide roller b⁷ is also mounted on the cross heads G at the inner side of the cylinder I.

The cross heads G² are provided with 75 arms h⁴ on which is mounted a guide roller b¹¹, at the inner side of the cylinder I². Cross heads G also have arms h⁵ carrying a guide roller b¹² at the outer side of cylinder I².

The roll of web w is mounted at the end 80 of the press opposite the drive mechanism where it is out of the way. The web roll is preferably mounted on a shaft 22 provided with a pulley 21 which is engaged by a brake shoe 20 pivoted on the frame of the press and having a cam arm 19 engaged by a roller on a lever 18 pivoted on the press frame; and lever 18 is connected by a rod 17 with a crank arm 16 on a rock shaft 15 carrying arms 14 in which is journaled a roller e which rests in a loop of the web W and automatically controls the feed of the web in a well known manner.

The web w passes from roll W over a 90 stationary guide roller b; down under the looping roller e; up over stationary guide roller b, mounted in the press frame; down under a stationary guide roller b³, journaled in suitable bearings on the press frame; and then passes back to the feed roll d.

The feed roll d is driven by pinion d² on its shaft meshing with an intermediate gear d³ which in turn meshes with a driving pinion d⁴ on the shaft c² of the crank gear 105 so that the feed roll is driven from the crank gears C by direct and simple means.

From the feed roll d the web passes onto and around a guide roller b⁴, mounted in the press, and then passes horizontally to 110 along and over the first looping roller e.

The looping roller e is mounted in the upper ends of rocking levers f mounted on a shaft g journaled in the main frame. The lower end of one or both levers F is pivotally connected by a rod f² to the lower end of a lever f³ which is pivoted at f⁴ on the main frame. The lever f³ carries a roller f¹⁰ which is adapted to engage an equalizing cam f⁵ affixed to the shaft of the feed roller d so as to turn uniformly therewith, the cam therefore being driven by the same gearing which drives the feed roll, doing away with any special gearing for operating this cam. The cam is so constructed as to oscillate the lever F at the proper time to cause the looper e to take up or give out the web as required in the operation of the press. The cam f⁵ is operated (1 to 1) with the roll d. The cams f⁵ may be inset in the 120 125 130

main frame to save width of press and insure proper alinement of the levers and parts when operated.

In the construction shown the cam f^5 is a plane cam and the roller f^{10} on the lever f^3 is held continuously in contact therewith by a suitable spring. As shown one end of a rod f^6 is pivotally connected to the lower end of the lever f , and the other end of this rod is guided in an eye f^7 on the main frame; and a helical expansion spring f^8 is interposed between the stop f^7 and a collar f^9 on the rod f^6 . The spring f^8 acts to rock the lever f^3 in one direction against the action of the cam and holds the roller f^{10} closely in contact with the periphery of the cam. Obviously a race cam might be employed if desired in place of the plane surfaced cam.

From the looper e the web passes horizontally to and over a stationary guide roller b^5 journaled in the frame of the press; then to and up over a stationary roller b^6 suitably mounted in the frame of the press; then the web passes to and over the roller b^7 under the cylinder I , up over the guide roller b^8 on cross heads G ; and then to and over an adjustable register roller b^9 adjustably mounted on the frame in any suitable way.

As shown roller b^9 is mounted in slidable bars 28 which can be adjusted by hand wheels 29 in the usual manner. From the register roll b^9 the web is led back, above the cylinder I to and over the guide roller b^{10} ; then down to and over the guide roller b^{11} on cross heads G^2 ; then under the cylinder I^2 , up over the roller b^{12} ; then horizontally outward to a second looping roller j .

The second looping roller j is mounted in the upper ends of oscillating levers k which are pivoted at k' on the frame of the press and the lower end of the levers k are pivotally connected to the upper ends of the levers f by link rods n , so that the looping rollers e and j will be operated synchronously and simultaneously in opposite directions, one roller taking up web as the other roller gives it out, and vice versa. Both looping rollers e and j are controlled by the cam f^5 . From the looping roller j the web passes to the delivery roll p which is driven in unison with the feed roll b .

As shown in Fig. 3 a bevel pinion 4 is affixed to one end of the roll d and meshes with a bevel pinion 4^a on a vertically disposed shaft 5 journaled in brackets 5^a attached to one of the side frames of the press, and having a bevel pinion 6 on its upper end meshing with a bevel pinion 6^a on the shaft of the roll p .

The feed roll d and delivery roll p are made of such diameter that they will for each rotation feed and deliver the exact length of web required for each newspaper

at each rotation thereof. The feed roll is preferably provided with the usual coating tapes d^s to assist in feeding web; and the delivery roll p also provided with coating tapes p^s as indicated in the drawings, such tapes being well known need no further description herein.

From roll p the web is led to and over a spacing roller q mounted in arms r on a rock shaft r' , journaled on the frame and provided with suitable means (not shown) for adjusting and holding the roller q in the desired position. The roller q is used to adjust the length of web between the delivery roll and the cutting cylinders, so that the cutting cylinders will sever the papers in the margins between the successive papers, after the web has passed the folder former.

The web is slit longitudinally as it passes over the roll p by means of a slitter p^3 of any suitable construction, as indicated in the drawings. The halves of the web after they pass the roller q are turned over angle bars S, S' and directed thereby toward the folder located at one side of the press. As shown in Fig. 3 one half of the slit web passes directly to the out feed roller 9 at the top of the former t while the other half of the web passes over a roller b^{13} down under an adjustable roller b^{14} then up to the roller 9 where the split webs are assembled before passing down the former t of the folder.

The former t is of the usual construction and thereby the two assembled sections of the web are folded into page width, and the thus folded four thicknesses of web pass down between the pinching rollers u^1 and u^2 and between the male and female cutting cylinders v^1 and v^2 , whereby the webs are severed into page lengths. Just before the portion of the web depending below the cylinders v^1 and v^2 is severed, it is tucked between the folding rolls x^1 and x^2 by the action of a tucker blade w^5 , and thus the paper is given the half page fold. The tucker blade w^5 may be operated in the usual manner. The severed paper is then carried by usual tapes x^3 and x^4 up over the last pair of folding rollers y, y over which the said half page folded papers are arrested by a stop, and when properly positioned the papers are tucked down between the rollers y, y by tucker blade z and packed in the usual packer box z^2 .

The folding mechanism per se form no parts of the present invention but a novel feature of the invention is the means for operating the folding mechanism synchronously with and directly from the press without using gearing or pulleys. For this purpose the folder is so located that the end of the cylinder v^1 is in direct alinement with the axis of the shaft C^2 carrying the main crank gears C . To the inner end of the shaft of the cutting cylinder V^1 is attached

4
a crank 42 the outer end of which is connected to a small wrist pin D^2 attached to the outer end of the wrist pin D by which the pitman E is connected to the crank gear C . By this means for each revolution of the crank gear c the cutting cylinder v^1 will make one revolution, being actuated by the crank 42 directly from the crank wheel C . By this means the transmitting shafts and 10 gearings usually required for driving a folder in synchronism with the press are dispensed with.

The cam 38 for operating the arm 39 carrying the tucker blade s may be mounted on 15 a shaft 38^c connected with the feed roll d (see Fig. 3). The cam 37 for operating the usual packing lever 35 may be operated by a cam 37 on the shaft 38^c ; these parts like shaft d being also operated in time (1 to 1) 20 with the other parts of the folder and press.

The folder is set at right angles to the press and beside the drive end thereof but all of the parts thereof are conveniently accessible to the pressman and by the means 25 described the parts of the folder are operated in proper time one to one for each reciprocation of the cross heads.

At the outer end of the bed O , and at 30 the end of the press adjacent the web roll, is an ink fountain U having a roll U^1 . An arm $12'$ is pivoted on the fountain and carries a pawl 12^x adapted to turn the fountain roll step by step when the arm $12'$ is vibrated. Arm $12'$ is adapted to be raised at 35 each outward stroke of cross heads G by a cam 13 on the cross head G , so as to shift the fountain roller each time that the cross heads G are moved to the limit of their outward stroke toward the web roll. From 40 the fountain roller the ink is taken by a ductor roller V mounted on the cross heads G and from ductor roller V the ink is transferred through intermediate distributing rollers Y to the form rollers Z . A similar 45 fountain U^2 is mounted on the feed end of the press and at the outer end of bed O^2 , the fountain roller being operated by a lever 12^a operated by a cam 13^2 on cross heads G^2 as the latter reach the end of 50 their outward stroke. Ink is taken from fountain U^2 by a ductor roller V^2 on cross heads G^2 and transferred through intermediate distributing rollers Y^2 to the form rollers A^3 .

55 No claim is made herein for the specific construction of the inking mechanisms therefore no more detailed explanation thereof is necessary.

Operation.

60 The operation of the various parts will be clear from the foregoing but may be summarized as follows.

The supply of web from the roll W is 65 automatically controlled by the governor

roller c in the usual manner so that an ample amount of free web is maintained in the press to supply the demands of the feed roll d but any tendency of the web roll to feed in an excess supply of web will be 70 arrested by the brake 20, which is automatically controlled by the position of the lever e . From the roll W the web w is led over the idler b , under looper c past idlers b^2, b^3 to the feed roll d by which it is fed 75 uniformly and continuously then passing over idler b^4 over the looping roller e over idlers b^5, b^6 to roller b^7 on the cross heads G then under cylinder I up over guide b^8 to the register roll b^9 . Then it returns 80 over the guide b^{10} to the guide b^{11} on cross heads G^2 then under cylinder I^2 up over guide b^{12} to the second looping roller j then to the delivery roller p then over guide q and then to the angle bars S, S' and to 85 the folder as above described.

The delivery roll operates continuously but in unison with the feed roll, and the looping rollers $e-j$ are so arranged and operated that on the printing stroke of the 90 press the movement of the web between the guide roller b^8 and guide roller b^{12} is arrested, although the web is continuously fed in and delivered. One side of the web is impressed by the cylinder I upon the 95 forms N on the bed O . The opposite side of the web is impressed by the cylinder I^2 upon the forms N^2 on bed O^2 .

At the end of the printing stroke (say 100 the stroke of the cylinders toward the web roll W) the cylinders are thrown off impression by action of the cam Q^2 engaging lever P^2 , and the cylinders then return off impression over the beds toward the driving end of the press to the position shown 105 in Fig. 1. As the cylinders reach the end of their off impression stroke they are thrown on impression by the levers P engaging the cams Q . On each or printing stroke of the cylinders and just before and during the printing operation the looping rollers $e-j$ are moved so as to stop the movement of the portion of web between the idler guide rollers b^4 and b^{12} ; but upon the completion of the printing operation 110 and after the cylinders are thrown off, the looping rollers $e-j$ are operated so as to shift through the press between the rollers b^4 and b^{12} as much web as had been fed into 115 the press during the printing operation. This amount of web is shifted through the press between the beds and cylinders while the impression is off in addition to the amount of web which is fed into and delivered from the press by the continuously 120 operating feed and delivery rollers during the time that the impression is thrown off.

With this press—for each complete reciprocation of the cross heads a perfected newspaper is printed, folded to quarter 130

page size, and delivered into the packer box by the mechanisms hereinbefore described.

What I claim is:

5. 1. In combination with a printing press having reciprocating cross heads, impression cylinders journaled in said cross heads, a shaft having cranks and connections between said cranks and cross heads, a folder 10 beside the press having cylinders parallel with the impression cylinders, and one of the cylinders being in axial alinement with the crank shaft; and a crank on one of the folder cylinder shafts connected with an adjacent crank on said shaft, whereby the 15 folder cylinders are operated synchronously with the cross heads.
2. In combination; reciprocating cross heads, and crank gears and pitmans for operating said cross heads; a folder having cutting cylinders one of which is in axial alinement with one of the crank gears; and a crank on said folder cylinder connected with the adjacent crank gear whereby the 25 folder cylinders are operated synchronously with the cross heads.
3. In combination with a printing press having reciprocating cross heads; a shaft, 30 wheels thereon having crank pins, and pitmans connecting said crank pins to the cross heads; a folder beside the press having cylinders parallel with the impression cylinders one of the folder cylinders being in axial alinement with the shaft carrying the crank 35 gears; and a crank on said folder cylinder shaft connected with the crank pin on the adjacent wheel, whereby the folder cylinders are operated synchronously with the cross heads.
4. In combination with a printing press 40 having impression cylinders, a shaft and a crank member on said shaft as set forth; a folder beside the press having cylinders parallel with the impression cylinders, one of the folder cylinders being in axial alinement 45 with the said shaft; and a crank on said folder cylinder shaft connected with the adjacent crank whereby the folder is operated synchronously with the press.
5. In a printing press, a main frame, a pair of crank wheels at opposite sides of the main frame, and a stationary type bed fastened to the frame and located between the crank wheels, a folder having cylinders one of which is in axial alinement with the shaft 50 carrying the crank gears; and a crank on said folder cylinder connected with the crank pin on the adjacent crank gear whereby the folder cylinders are operated synchronously with the cross heads. 55
6. In a printing press having a main frame, a shaft, crank gears thereon, a type bed, a cylinder operating on said bed, and means operated by said crank gears for moving the cylinder; a folder having cylinders one of which is in axial alinement with said shaft, and a crank on said folder cylinder connected with the crank pin on the adjacent crank gear whereby the folder cylinders are operated synchronously with the 60 cross heads. 65
7. In combination, a printing press having a shaft; a folder beside the press having cylinders; a crank on one of the folder cylinders; and a crank on the press shaft engaging the crank on the folder cylinder, whereby the folder is operated synchronously with the 75 press.
8. In combination with a printing press having an operating shaft; a folder beside the press having cylinders parallel with said shaft; a crank on one of the folder cylinders; and a crank on said shaft engaging the crank on the folder cylinder, whereby the folder is operated synchronously with the 80 press. 85

In testimony that I claim the foregoing as my own, I affix my signature.

PAUL F. COX.
